UNITED STATES PATENT OFFICE.

JULIUS REQUARD, OF BALTIMORE, MARYLAND.

DESIGN FOR A CIGAR.

SPECIFICATION forming part of Design No. 34,334, dated April 9, 1901.

Application filed March 5, 1901. Serial No. 49,971. Term of patent 7 years.

To all whom it may concern:

Be it known that I, JULIUS REQUARD, a citizen of the United States, residing at Baltimore, State of Maryland, have invented and produced a new and original Design for a Cigar, of which the following is a specification.

Reference is to be had to the accompanying drawings, illustrating the design, in which—

Figure 1 is a side elevation of the cigar embodying the features of the design. Fig. 2 is a similar view thereof at right angles to Fig. 1. Fig. 3 is a transverse vertical section on the line 3 3 of Fig. 1. Fig. 4 is a transverse vertical section on the line 4 4 of Fig. 1.

The design consists in the shape and configuration of the cigar shown in the accompanying drawings, which is approximately of oblong rectangular shape in cross-section—that is, with two wide and two narrow sides.

On the wide side and at the middle thereof is

a rectangular panel *a*, on which appears a plurality of stars, and also on said wide side are two series *b* and *c* of parallel corrugations or stripes, running lengthwise of the cigar toward the point and butt, respectively, one series being on one side of said middle panel and the other series on the opposite side of said panel. Both of the two wide sides of the cigar are alike, and the two narrow sides of the cigar are smooth, as shown.

30 I claim—

The design for a cigar herein shown and described.

In testimony whereof I affix my signature in the presence of two witnesses.

JULIUS REQUARD.
